(57) **CLAIM**

The ornamental design for a medical instrument for eye surgical purposes, as shown and described.

DESCRIPTION

Figure 3.1 is a perspective view of the medical instrument for eye surgical purposes showing our new design;

Figure 3.2 is a front elevation view thereof;

Figure 3.3 is a back side view thereof;

Figure 3.4 is a right side view thereof;

Figure 3.5 is a left side view thereof;

Figure 3.6 is a top view thereof; and

Figure 3.7 is a bottom view thereof.

The broken lines shown in Figure 3.7 illustrate portions of the medical instrument for eye surgical purposes that form no part of the claimed design.
